CORSET

Mercedes Nouel, Woodhaven, N. Y.

Application November 16, 1953, Serial No. 392,308

1 Claim. (Cl. 2—39)

This invention relates to surgical corsets.

In conventional surgical corsets, the separable back portions are secured together by laces which are in turn threaded through buckleplates adjustable along side straps secured at one end to each side of the corset. By adjusting the aforesaid buckle plates carrying these laces, it is possible to adjust the size of the corset to the dimensions of the wearer. However, the side straps along which the buckle plates are adjustable are secured at only one end to the body of the corset, the other ends of the straps being free to facilitate the mounting thereon of the adjustable buckle carrying the buckle plate. These free ends dangle in an unsightly manner and form objectionable protrusions visible through the outer garment.

It is accordingly a principal object of the present invention to provide in a surgical corset novel means for preventing the free ends of the straps from dangling in an unsightly manner.

A further object of the invention resides in the provision of means in a surgical corset for interconnecting the free ends of the side straps across the back or front of the wearer in a self-adjustable manner, said means reinforcing the corset proper.

A further object of the invention resides in the provision of a surgical corset which is sturdy and durable in construction, reliable and efficient in use and inexpensive to manufacture and assemble.

For other objects and a better understanding of the invention, reference may be had to the following detailed description taken in connection with the accompanying drawing, in which:

Figure 1 is an outside plan view of a surgical corset spread flat and showing the invention incorporated thereon;

Figure 2 is a transverse sectional view taken along the line 2—2 of Figure 1;

Figure 3 is a rear elevational view showing the corset in operative use;

Figure 4 is an enlarged detail view of the invention;

Figures 5 and 6 are rear views in elevation showing the corset in operative use.

Referring now more in detail to the drawing, and more particularly to Figure 1, there is generally indicated at 10 the surgical corset including a pair of separable back panels 11 and 12, the panels 11 and 12 along their adjacent vertical edges being provided with the usual eyes 13.

The back panels 11 and 12 are also provided along their lower edges with the usual V-shaped cut outs 14 across which are secured elastic material 15 by means of the stitching 16.

The usual vertical stays 17 extending from top to bottom of the corset are mounted on the inner faces of the back panels 11 and 12 by means of vertical pockets 18 secured in position by stitching 19 (Figure 2).

The outer vertical edge of the back panel 11 is secured to a left panel 20 by the stitching 19a (Figure 2), decorative border strips 21 being provided on the upper edge

2

of the back panel 11 and overlapping the inner edge of the side panel 20. Decorative border strips 22 are provided on the lower edge of the side panel 20 and extend inwardly to the cut out 14. An inner decorative border strip 23 is also provided on the lower edge of the back panel 11.

A reinforcing strip 24 is secured to the outer vertical edge of the side panel 20 by means of stitching 25 (Figure 1), the strip 24 being provided with vertically spaced eyes 26. A decorative border strip 27 connects the upper edges of the strip 24 and side panel 20 and is secured in place by stitching 28.

A left upper side strap 29 is secured at one end intermediate the adjacent edges of the back panel 11 and side panel 20, a buckle 30 being adjustable along strap 29 and pivotally mounting a plate 31 having a plurality of openings 32.

A bottom left side strap 33 has one end secured in position by a reinforcing flap 34 and stitching 35, the flap 34 being secured to the side panel 20 by the stitching 36 and 25. A second buckle 37 is adjustable along the strap 33 and pivotally mounts a second plate 38 provided with a plurality of openings 39. Loops 40 and 41 of flexible material are secured at opposite ends intermediate 25 the adjacent edges of the back panel 11 and side panel 20 and serve to surround the straps 29 and 33, respectively, in the manner shown.

A right side panel 42 is similarly secured along its vertical edge to the adjacent vertical edge of the back panel 12 by means of stitching 43, which latter also serves to mount the right upper side strap 44, the upper loop 45 and the lower loop 46. Decorative border strip 47 is provided along the upper edge of the back panel 12 and overlaps the right side panel 42.

A buckle 48 is adjustable along the upper right strap 44 and pivotally mounts a plate 49 provided with a plurality of openings 50.

A front panel 51 is secured along one vertical edge to the adjacent vertical edge of the right side panel 42 by means of stitching 52, the front panel 51 being provided with vertical stays 53 secured by stitching 54. The front panel 51 at its center is provided along its lower edge with an upwardly extending, V-shaped cut out 54' adapted to be aligned with the crotch of the wearer when the corset is in the wearing position of Figure 3, elastic material 55 being disposed across cut out 54' and secured in this position by the stitching 56. A decorative border strip 57 is secured to the upper edge of the front panel 51 and overlaps the right side panel 42, while a decorative border strip 58 is secured to the lower edge of the front panel adjacent the outer end thereof. A decorative border strip 59 is secured to the lower edge of the right side panel 42 and overlaps both the front panel 51 and the rear panel 12 (Figure 1).

A plurality of vertically spaced hooks 60 are mounted on the inner face of the front panel 51 along the outer vertical edge thereof, the hooks 60 being adapted to engage the eyes 26 whereby to secure the corset about the wearer, as shown in Figure 3.

A lower right side strap 61 is secured in position by a reinforcing flap 62 and stitching 63, the flap 62 being in turn secured by stitching 64 to the right side panel 42. A buckle 65 is adjustable along strap 61 and pivotally mounts a plate 66 having a plurality of openings 67.

The usual stocking support straps 68 are suitably mounted at the lower edges of the back panels 11 and 12.

A continuous lacing 69 is threaded through the openings 39 and 67 in the plates 38 and 66, respectively, and certain of the eyes 13, whereby to connect the back panels 11 and 12 together in the manner indicated. A second continuous lacing 70 is similarly threaded through

the openings 32 and 50 provided in the plates 31 and 49, respectively, and through uppermost eyes 13.

In the usual manner of surgical corset constructions, by adjusting the buckles 30 and 37 laterally away from the buckles 38 and 65, respectively, the lacings 69 and 70 will be subjected to a tension, thus drawing the adjacent edges of the back panels 11 and 12 closer together and tightening the corset about the wearer.

In the practice of my invention, the free ends of the straps 29, 33, 44 and 61 are folded back upon themselves in the manner shown and are secured in this position by stitching 71, 72, 73 and 74, respectively, providing reinforced ends. These doubled-up end portions are provided with aligned openings therethrough through which are threaded elastic cords 75, 76, 77 and 78. The inner ends of the cords 75, 76, 77 and 78 are knotted to secure the cords within the reinforced ends in the manner indicated. The other ends of the cords remain free until the corset is mounted upon the wearer as shown in Figure 3. Then, the adjacent pairs of cords are bow-tied across the back of the wearer. Thus, the cord 75 is bow-tied to the cord 77, while the cord 76 is bow-tied to the cord 78. This stretches the free ends of the straps 29, 33, 44 and 61 so as to lie flush with the rear face of the corset and avoids thereby unsightly dangling and the forming of objectionable obstructions visible through the outer garment. The connection of these free ends across the back of the wearer it will be noted, further reinforces the lacings 69 and 70. Preferably, eyes 79, 80, 81 and 82 are provided in the doubled-up ends of the straps 29, 33, 44 and 61, respectively.

Thus, by doubling the ends of the straps 29, 33, 44 and 61 back upon themselves and providing the stitching 71, 72, 73 and 74, these free ends are reinforced and receive therethrough the ends of the elastic cords 75, 76,

10

77 and 78, the eyes 79, 80, 81 and 82 reinforcing the openings in the reinforced ends.

By securing the elastic cords 75 through 78 across the back of the wearer, the

free ends of the straps 29, 33, 44 and 61 are prevented

from dangling in an unsightly manner and further re-

inforce the lacings 69 and 70.

Figures 5 and 6 show upper straps 44 and 29 and lower straps 62 and 33 secured across the front and side of

the wearer.

While various changes may be made in the detail construction, it shall be understood that such changes shall be within the spirit and scope of the present invention as defined by the appended claim.

What is claimed is:

15 A corset comprising a plurality of panels and at least one pair of cooperating adjustment straps each secured at one of its ends to one of said panels, each of said straps carrying an adjustment buckle through a strap loop, each of said buckles having openings therein, lacing 20 threaded through said openings in each of said buckles for connecting said cooperating adjustment straps, a loop through which each of said adjustment straps and the free loop ends thereof are adapted to pass and being secured to different corset panels, an elastic strip for each 25 of said straps secured to the free ends thereof and being adapted to be tied together under tension to maintain the strap ends in taut and aligned positions.
